UNITED STATES PATENT OFFICE

CHARLES F. HEYWOOD, OF DETROIT, MICHIGAN, ASSIGNOR TO SKY SPECIALTIES CORPORATION, OF DETROIT, MICHIGAN, A CORPORATION OF MICHIGAN

INTERNAL-COMBUSTION ENGINE

Application filed June 11, 1927. Serial No. 198,255.

This invention relates to the operation of internal combustion engines, pertaining more particularly to the starting of such engines, and which, by continuance of the starting 5 activities indefinitely, may also serve for the running activities of the engine.

One of the difficulties in connection with the operation of engines of this type is produced by the conditions present in producing 10 the proper admixture of the air and fuel for the carburetted charge; this is especially made manifest when starting the engine, and is brought about by the necessity of bringing the air into close proximity to the fuel 15 discharge of the carburettor in order to obtain the desired amount of fuel for the charge. This is especially true in starting, since the content of the intake manifold has little or no fuel component within the content while 20 the engine is at rest, and it becomes essential to bring that content to a fuel-laden condition of the air in order to ensure proper operation. As a result, it is generally the practice to throttle the air supply at this 25 time in order to obtain a heavy suction effect upon the fuel, the consequence being that the volume of air introduced is not properly proportioned to the fuel component that is being carried into the engine. 30 The charge for the cylinder that is drawing the fuel-laden air is thus introducing a charge that is rich in fuel content but lean with respect to the air content, when compared with a normal charge.

35 Under such practice, the charge is introduced during the suction stroke period of the cylinder, the charge being assumedly compressed during the succeeding compression stroke period; but lack of the proper 40 volume of air within the charge introduced under these conditions of a "choking" throttle action, leaves the charge with an insufficient amount of air to provide combustion of all of the fuel which is introduced as 45 a component of the charge, as well as setting up the conditions of an insufficient volume of the air and fuel mixture to provide for proper compression conditions—instead of obtaining a compression value of say sixty 50 pounds pressure within the cylinder, the

pressure value may be less than twenty per centum (20%) of such value, with a consequent loss of power when the gaseous mixture is fired. And in some cases, the practice sets up the conditions of a practically 55 flooded cylinder, due to the large excess percentage of fuel content in the mixture, the air of which is insufficient to provide for the proper and complete combustion of the entire fuel content. Under these conditions, 60 the general practice is to turn over the engine several times, with the choke active, to prepare the intake manifold, and then, upon release of the choked condition, permitting a larger amount of air to enter and begin 65 to prepare the cylinders for the normal action by production of a gaseous mixture which more nearly conforms to the proper percentages of its component elements.

These difficulties can be overcome by augmenting the supply of air to the cylinder undergoing compression, doing this by introducing air from a different source to such cylinder during the compression activities; and this can also take the form of the use 70 of a carburetted air, if desired, so that the charge itself can be introduced from this different source for starting purposes—or can form the source of charge supply for running purposes, if necessary or desirable. 75 The latter characteristics is presented in the invention disclosed in the U. S. patent granted to me January 15, 1924, No. 1,481,091, wherein the working cylinder is subjected to the activity of a compressed air charge, and 80 the compression cylinder is given a carburetted charge of lesser volume within the period during which the working cylinder is receiving its charge; the patent disclosure also presents the condition that the charge 85 for the working cylinder may also be of carburetted fluid, if desired; and such patent disclosure also contemplates the introduction of a carburetted charge into the cylinder undergoing suction, with the charge 90 of lesser volume than that of either the compression or working cylinders.

In its broader aspects, the present invention has some of the general characteristics of such earlier patent—the delivery of a 100

charge to the compression cylinder of lesser volume than that to the working cylinder, being one of these characteristics. The present invention, however, distinguishes in a number of respects from that of the earlier disclosure. Among these is the ability to use air alone within the control apparatus, supplying the fuel from a different source; or the apparatus may use a carburetted charge for both working and compression cylinders—this practice, while serviceable, would, under ordinary ignition conditions, tend to waste fuel, since the delivery of a fuel component as a part of the charge which is active in the working cylinder only after the cylinder has been fired, would leave the fuel content without combustion activity and therefore inactive excepting for the service it is performing as a part of the compressed fluid and be discharged through the exhaust with the remainder of the fluid; this wastage can be avoided by the use of an ignition made active during the power stroke period.

Another distinction is the use of a single port for control purposes within the valve in place of the independent ports of the earlier disclosure. Other distinctions are present as will be seen by a comparison of the two disclosures, one of these being, for purposes of illustration, the use of the carburetter as the source of the fuel component of the charge, this enriched charge being introduced on the suction stroke, as above indicated, after which the air component is augmented through the apparatus during the compression stroke activity of the cylinder. In the latter case, the carburetter activity is being developed during the starting operation, and hence is properly functioning when the starting apparatus is made inactive after starting.

Among the objects of the invention, therefore, is to be found the augmenting of the air supply of a carburetter-served engine subsequent to the admission of the balanced or unbalanced carburetter charge and prior to the ignition of the charge; to increase the compression value of the charge prior to ignition by the introduction of air to the cylinder undergoing compression; and to provide a simple and efficient arrangement of parts by which the starting and operation of the engine will be had.

To these and other ends, the nature of which will be readily understood as the invention is hereinafter disclosed, said invention consists in the improved construction and combination of parts hereinafter fully described, illustrated in the accompanying drawings, and more particularly pointed out in the appended claims.

In the accompanying drawings, in which similar reference characters indicate similar parts in each of the views—

65 Figure 1 is a fragmentary elevation, some-

what diagrammatic in character, of an engine equipped with an apparatus embodying the said invention;

Fig. 2 is a detail sectional elevation of the valve mechanism shown in Fig. 1;

Fig. 3 is a transverse sectional view taken 70 on the line 3^x—3^x of Fig. 2;

Fig. 4 is a diagrammatic view of a modified form of valve mechanism adapted for a six-cylinder engine.

Fig. 5 is a fragmentary sectional view 75 showing one of the check-valve assemblies.

For the purpose of illustration of the invention, I have shown that form of the invention in which the fuel component is introduced through the carburetter of the engine, the device of the present invention utilizing compressed air alone in providing the activities. And in presenting this I have shown it as applied to a four-cylinder engine of an ordinary type; this, however, is more or less illustrative, as the invention is adapted to be used with various types, both as to number of cylinders as well as to the arrangement of them, and the illustration used is therefore 90 not to be considered as of limiting characteristic.

In the drawing, 1 indicates a four-cylinder engine, having the cylinders I, II, III and IV, numbered in their firing order, 2 indicating a part of the inlet manifold to which is connected a carburetter 3. The inlet valves are indicated at 4, while 5 indicates the exhaust valves. The specific details of these and the arrangements internally of the engine are not specifically illustrated as they are of the usual type and are well-known.

Mounted in the head of the engine are check-valves 6 which control the conduits 7, 8, 9 and 10, and which lead to the respective cylinders, the check valves being adapted to open when the pressure within a conduit exceeds that within the cylinder, and to close when the pressure conditions are reversed; a conventional form of check-valve adapted for the service is illustrated in Fig. 5. The conduits 7 to 10 are shown as leading to passages I^a, II^a, III^a and IV^a, of a valve casing 11, this numbering of the passages being used for convenience in indicating the association of a particular passage with a particular cylinder in the form illustrated, the arrangement being more particularly to bring out the order of firing of the cylinders and the order of activity of the passages.

120 The valve casing includes a hollow cover plate 12 to provide a chamber 13, said chamber being adapted to receive compressed air from a tank 15, the latter being connected with chamber 13 by a valve-controlled pipe 14, 125 the valve being indicated at 16 and which may be operated by a rod 17.

Within chamber 13, and disposed over the inlet ends of passages I^a, II^a, III^a and IV^a, of the valve casing, is a rotary valve 18, 130

adapted to be rotated by a shaft 20, driven by gearing 21 from a driven shaft 22 of the engine and which may be the engine cam shaft, the arrangement, in this particular instance, providing for rotation of the valve at half engine speed. The valve 18 is shown as provided with a port 19 which extends transversely of the valve and arcuately thereof, with the arc positioned so that the valve, in rotating, will bring the port opposite the entrance to the passages I^a, etc., at proper times, thus permitting the compressed air from the chamber 13 to enter the conduits and become active within the cylinders.

In theory, the strokes of the Otto cycle represent the periods of activity of the four different activities comprised in the cycle, thus making each of the periods equal to 180° of the movement of the crank-shaft. In practice, however, and especially with engines of the high-speed type, the timing is arranged to present considerable variation from the theoretical "strokes". For instance, the firing of the charge takes place in advance of the position where the piston is at the end of its outward stroke, thus permitting the propagation of the charge explosion to take place and become complete about the time when the piston has just passed the "dead center position"; the advance is variable according to the speed, and may be as much as 30° of the crank shaft travel. Since the latter portion of the inward working or power stroke is of little value in the development of power, the timing of the exhaust valve is generally arranged to be opened in advance of the completion of this stroke; the advance may be so much as 50°, so that the power stroke would be approximately 130° of the crank shaft travel of this inward stroke. The exhaust stroke thus is approximately 230° of the crank shaft travel, completing the first rotation of the crank. The suction stroke which follows, and during which the charge of fuel is admitted, generally continues past the end of the stroke, reaching approximately 40° beyond this point, so that the intake is approximately 220° of the travel of the crank shaft, the compression stroke then being active for approximately 140° of the travel of the crank shaft; during this latter period the charge is ignited as above pointed out.

The starting system herein disclosed is illustrated to operate under the approximate conditions thus referred to. The compressed fluid for the power stroke is admitted when passing or shortly after the crank has passed the dead center—this will be explained hereinafter—and the admission is closed when the crank shaft has travelled approximately 115° of the power stroke; this ending in advance of the opening of the exhaust valve is preferred, since it tends to economize in the use of the compressed fluid, expansion being

permitted and thus reducing the amount of fluid which is discharged during the exhaust. It is to be understood, of course, that the ending of the fluid admission may be delayed until the exhaust valve opens, but this increases the amount of fluid admitted, and hence tends to wastage. The admission of fluid to the compression cylinder begins approximately 80° in advance of the dead center position of the crank, thus beginning its admission at an intermediate point of the travel of the piston during the compression stroke.

In illustrating these distances in Figs. 2 and 4, the distances are indicated as one-half of these values, since the valve 18 is travelling at one-half the engine speed, one revolution of the valve disk representing the two revolutions of the crank-shaft in completing the cycle. In these views, the entrances to passages I^a, II^a, etc., are indicated as of 20° angular length and preferably circular, the body of the port being indicated as being of a width corresponding to the diameter of such circle; the advance end or toe 19^a, however, is considerably reduced in width, since it is desired that the volume of air admitted to the compression cylinder per unit of time be materially less than that admitted to the working cylinder during such unit of time, thus producing a material preponderance in volume of admitted air in favor of the working cylinder in a particular unit of time during which delivery is being made to both compression and working cylinders concurrently; hence there is no opportunity of balancing of pressures between the two cylinders—a condition which would tend to prevent starting.

As heretofore pointed out, the present invention has, as one of its distinctions from the disclosure of the earlier patent referred to, but a single port in the valve disk in place of the independent ports shown in the earlier disclosure. This change has the effect of eliminating the portion of the valve which divided the two parts of the earlier structure, and which served to provide a physical break in the delivery of fluid during the period when the division portion was in position over a passage entrance. However, this result is obtained automatically in the present invention, due to the presence of check-valves 6, and the fact that the pressure developed in the cylinder which has been fired becomes temporarily greater than the pressure of the compressed air; this cylinder pressure reaches to approximately five hundred or more pounds per square inch, while the pressure of the compressed air is approximately four hundred pounds per square inch. Hence, it will be understood that the instant the cylinder pressure becomes dominant in value, the check-valve 6 of that cylinder will close to prevent admission of air, and will remain closed until the pressure of the compressed air again becomes dominant, this

occurring shortly after the crank has passed the dead center position. The port 19 is so arranged that the body of the port is open to the entrance to the passage leading to the cylinder when the check-valve opens, so that the greater volume is then admitted to the cylinder. An advantage of this arrangement is found in the fact that the time of ending of the air admission to the cylinder under-
10 going the compression activity is made wholly dependent on the development of the cylinder pressure, as is the beginning of admission of air to the cylinder in its working stroke; as long as the cylinder pressure is
15 dominant, air will not be admitted. The period of temporary cessation of air delivery may vary as to length, but the conditions are such that delivery of air in proper amounts will be present the instant the check-valve
20 will permit.

The arrangement of Fig. 2 is that for a four-cylinder engine, with the passage entrances 90° apart. In Fig. 4, the arrangement is indicated as for service with a six-
25 cylinder engine, the entrances being 60° apart; however, the valve is shown as having the port 19 as similar in both cases, it being readily understood that with each cylinder the cycle development is the same regard-
30 less of the number of cylinders present, and the activity of port 19 is based on the cylinder cycle. With the system installed in connection with an eight-cylinder or a twelve-cylinder engine, the valve can be the same as
35 with those illustrated, the twelve-cylinder service preferably utilizing only six of the twelve cylinders in connection with the system and thus utilizing the arrangement of Fig. 3. It will be understood, however, that
40 I may, if desired, vary the port dimensions from either of the engines, and may vary them from those indicated, the present disclosure of dimensions being more or less illustrative and designed to show one of the
45 dimension characteristics which can be employed.

In Figure 2 the port 19 is shown as fully uncovering the entrance to passage I^a, this position indicating that the crank has ad-
50 vanced a distance of 40° past the dead center (20° in the travel of the disk—the rear edge of the passage entrance I^a being considered as the dead center position). At this instant, the leading end of the nose 19^a of the port is
55 shown as 40° (80° of crank-shaft travel) advanced toward the entrance of passage II^a which leads to the cylinder undergoing compression. A further advance of the valve a distance of 30° (60° of crank-shaft travel)
60 brings the leading end of the nose 19^a to the passage II^a, at which time the body of the port is still admitting air to passage I^a, al-
though the delivery to the latter passage ends shortly afterward (approximately 7° of
65 the valve travel). The cylinder of passage

II^a is thus being prepared for the ignition action on its compressed content, to be followed by the temporary cessation of delivery and the further air delivery during the working stroke.

In Figure 4 the leading end of the nose 19^a is shown as in a position about to establish communication with passage II^b, while passage I^b has just been fully opened to the body of the port; the position of the body of the port is thus shown as the same with respect to passages I^a and I^b in Figs. 2 and 4, the difference between the two disclosures being the position of the leading end of the nose 19^a of the port relative to the passages II^a and II^b, respectively. This difference, however, does not affect the operation which remains the same in both cases, due to the fact that the position of the piston of the cylinder under compression (II^a and II^b) is the same in both cases; in Fig. 2, the position of passage II^a represents the position of the piston of the cylinder served by this passage at the diametrically opposite point (the beginning of the compression stroke) from that of the beginning of the power stroke—the crank then turning an angular distance of 60° (30° of the travel of valve 18) when the leading end of the nose becomes active by the travel of the valve during this angular distance; in Fig. 4, the different setting of the cranks has the effect of placing the position of the crank of the cylinder served by passage II^b this same distance of 60° advanced beyond the diametrically opposite (the beginning of the compression stroke) point from the position of the crank of the cylinder which is beginning its power stroke, and hence has reached the same position of the piston as is reached by the piston of the cylinder served by passage II^a in Fig. 2.

In other words, the length of the port of valve 18 depends on the travel of an individual piston and its strokes in the comple-
110 tion of the Otto cycle, this port length in-
cluding approximately 198° of the angular travel of the crank-shaft in completing the two revolutions of the cycle, the port becom-
115 ing active with respect to the entrance of a passage to a cylinder when the crank of the piston of that cylinder has travelled approxi-
120 mately 60° of the angular distance of its compression stroke, and continues active with such entrance until the piston ap-
125 proaches the position of beginning the ex-
haust of the cylinder during the latter part of the power stroke. The position of the en-
trances I^a, II^a, I^b, II^b, etc., relates to the time when this activity of the port begins with a cylinder. The nose of the port thus delivers to the cylinder during the compres-
130 sion stroke, while the body of the port de-
livers to the cylinder during the power stroke,

this action taking place with the cylinders successively in the order of their firing.

It will be readily understood that I have referred to compressed air as the fluid used in the operation; however, as heretofore pointed out, the compressed fluid may be a carburetted air, in which case the fluid delivered to the cylinder that is undergoing compression would itself become a combustible charge therein, and hence capable of being fired irrespective of carburetter action, so that the carburetter could remain inactive; in fact, it would be possible to run the engine indefinitely without carburetter activity, with the combustion charge introduced in this way. However, with compressed carburetted air as the compressed fluid, the portion admitted during the power stroke would not be fired—excepting under the conditions heretofore referred to—and hence the fuel component of this portion of the fluid would be a loss. Because of this condition, I prefer to use compressed air as the active starting fluid in this particular type of mechanism, using the carburetter as the source of fuel supply.

And in this latter connection, it will be readily understood that the air supply to the carburetter may be throttled or "choked", since the supply of air for the charge is not directly dependent upon that received through the carburetter, since a part, at least, of the air component of the charge is delivered into the cylinder through nose 19^a. As a result, the greater richness of the fuel introduced through a "choked" throttle does not become a disadvantage, since sufficient air for combustion will be provided. Should the charge develop a greater pressure condition within the cylinder, the effect would be made manifest on check valve 6, and thus delay its opening within the power stroke; no disadvantage would result from the latter since the piston is then being driven by a pressure at least equal to that of the compressed air. When, however, the cylinder pressure becomes reduced in value to an amount as to become subordinate to that of the compressed air, check-valve 6 opens and brings the compressed air into activity to continue the drive of the power stroke until the port passes out of operative relation to the entrance of the passage leading to the cylinder being served, this latter time being the same at all times since the port is of fixed dimensions. Should the charge be lean, and hence insufficient to develop when fired a cylinder pressure sufficient to close check-valve 6, the greater volume of air which would then be introduced into the working cylinder will cause the engine to carry the piston of the cylinder which is to become active as the next working cylinder, past its dead center, the greater volume of

air which then becomes active in the cylinder carrying the engine onward.

It will be understood, of course, that, if desired, the fuel content of the intake manifold may be augmented for starting by a direct priming action. And this type of providing for the fuel content of the charge may be used even to the extent of entirely eliminating carburetter activity during the starting operation, the fuel content being provided through the primed intake manifold, while the air content of the charge is provided by the compressed fluid entering through nose 19^a. And it will be more or less obvious that, if desired, a cylinder or cylinders may be primed preliminary to starting, whether the content of the intake manifold be of carburetter or priming source or both, or be inactive to deliver fuel during the period of starting. These methods are made possible through the fact that the mechanism is so formed and operated that there is always a delivery of the compressed fluid to the cylinder next in firing order sometime during the period subsequent to the suction stroke of the cylinder and prior to the firing period of the cylinder, thus supplying an air content thereto such as will enable the production of a compressed charge of a value such that combustion of fuel content will be had when ignition is provided, with the resultant pressure active in developing running of the engine.

It will be understood, of course, that the specific dimensions and configuration of the port 19, 19^a, are more or less illustrative, being those of a preferred form and dependent more or less on engine characteristics of a general type. The dimensions and configuration may be varied to meet different conditions. For instance, if it be desired that the fluid for the cylinder undergoing compression be introduced later in the period of the compression stroke, the nose 19^a will be made shorter, while the amount to be admitted may be retained by increasing the width of the nose. Similarly, the arc length of the body 19 of the port may be shortened or lengthened according to the needs of a particular type of engine, as where the timing of the exhaust valve opening is changed from that indicated above, or the delivery of air on the power stroke may extend closer to the time of exhaust, if desired. The mechanism is suitable for use with all types of engines and it may be necessary to form the port to meet the characteristics of an individual type; and such changes are contemplated within the general disclosure made herein.

The mechanism is obviously usable with engines having a greater number of cylinders than the two types referred to herein (the four and six cylinder types). In the eight or nine cylinder types, the mechanism would preferably be arranged to deliver to

each of the cylinders. This could also be done with the twelve-cylinder type, if desired, but this type will be effectively operated by connection with but six of the twelve cylinders, 5 with the mechanism operating as in the six-cylinder type of the disclosure. These are to be considered as detail characteristics more or less individual to special types of engines, and would be embodied within the general 10 invention herein disclosed.

While I have herein shown and described one or more ways in which the invention may be embodied, it will be readily understood that changes and modifications therein may 15 be found desirable or essential to meet the various exigencies of use, and I desire it to be understood that I reserve the right to make any and all such changes and modifications therein as may be found essential or desirable, in so far as the same may fall within 20 the spirit and scope of the invention as expressed in the accompanying claims when broadly construed.

Having thus described my invention, what 25 I claim as new is:—

1. In means for starting multi-cylinder internal combustion engines, wherein compressed fluid is admitted to and is active in developing piston movement in the working 30 cylinder of the cycle, a source of fluid supply, and connections between such source and individual cylinders of the engine, said connections including valve mechanism for controlling the delivery and distribution of the 35 fluid to the respective cylinders, and conduits leading from the valve mechanism to the cylinders individually with the mechanism having uniformly-spaced entrances to such conduits, each conduit having a check-valve 40 adapted to be closed by cylinder pressure, said mechanism including a rotatable member operatively connected to move in synchronism with the engine crank shaft, said member having a port adapted to be made active 45 with the conduit entrances successively, said port having dimensions and a configuration such that fluid will be delivered to the working cylinder to provide power therein and that fluid will also be delivered to the cylinder 50 next in firing order, the volume of fluid delivered to the working cylinder being materially greater than that delivered to the cylinder next in firing order.

2. Means as in claim 1 characterized in that 55 the pressure value of the compressed fluid is greater than the normal compression value of the cylinder next in firing order and of less value than the explosion pressure of such 60 cylinder, whereby delivery of fluid to the cylinder undergoing compression will be temporarily stopped by check-valve activity when the charge of such cylinder is ignited and will be resumed as the pressure developed by 65 explosion in such cylinder becomes less than

the fluid pressure value active within the period of the working stroke of the cylinder.

3. Means as in claim 1 characterized in that the member port is elongated in the direction of travel of the member, with the advance 70 end of the port of less dimensions than the body of the port. 75

4. Means as in claim 1 characterized in that the member port is elongated in the direction of travel of the member, with the advance end of the port of less dimensions than the body of the port, the member movements being being timed in such manner that the firing of the cylinder undergoing compression takes place in advance of the arrival of 80 the body of the port at the entrance to the cylinder conduit, whereby the advance end of the port will deliver fluid to the cylinder to be fired and the body of the port will deliver fluid to the cylinder after such firing has taken 85 place. 90

5. Means as in claim 1 characterized in that the member port is elongated in the direction of travel of the member, the member movements being timed in such manner that the port will be active with the entrance to cylinder conduit to deliver fluid thereto both prior and subsequent to the firing of the charge of that cylinder, delivery of fluid to such cylinder through such entrance being rendered inactive temporarily within the cylinder by the preponderance of pressure value within the cylinder of the explosion pressure during the firing period by check-valve activity. 95

6. Means as in claim 1 characterized in that the member port is elongated in the direction of travel of the member, the member movements being timed in such manner that an intermediate portion of the port is open to the entrance to the conduit of a cylinder during the firing period of that cylinder, whereby fluid delivery to the cylinder will be provided in advance of and subsequent to the firing of the charge of the cylinder, temporary cessation of fluid delivery thereto being provided by check-valve activity in presence of a preponderance of pressure within the cylinder as a result of the firing activity. 105

7. Means as in claim 1 characterized in that the member port is elongated in the direction of travel of the member, with the port length such that delivery of fluid to the working cylinder and to the cylinder next in firing order will be concurrent. 115

8. Means as in claim 1 characterized in that the member port is elongated in the direction of travel of the member, with the port length such that delivery of fluid to the working cylinder and to the cylinder next in firing order will be concurrent, the length of time of delivery within the working cylinder being greater than that within the cylinder next in firing order. 125

9. In means for starting multi-cylinder in- 130

ternal combustion engines, wherein the fuel content of the charge to be fired is delivered to the cylinder through intake manifold operation during the suction stroke, and wherein compressed fluid is admitted to and is active 5 within the working cylinder to develop piston movement in such cylinder during starting activity, a source of compressed fluid supply, and connections between such supply 10 source and individual cylinders of the engine, said connections including valve mechanism for controlling the delivery and distribution of the fluid to the respective cylinders, and conduits leading from the valve mechanism to the cylinders individually with the mechanism having uniformly-spaced entrances to such conduits, each conduit having a check 15 valve adapted to be closed by cylinder pressure produced by firing of the charge, said mechanism including a rotatable member operatively connected to move in synchronism with the engine crank shaft, said member having a port adapted to be made active with the conduit entrances successively, said port 20 having dimensions and a configuration such that fluid will be delivered to the working cylinder to provide power therein and that fluid will also be delivered to the cylinder next in firing order to complete the air content of the charge of such latter cylinder prior to the firing period of the charge therein, the volume of fluid delivered to the working cylinder being materially greater than that delivered to the cylinder next in 25 firing order.

10. Means as in claim 9 characterized in that the pressure value of the compressed fluid is greater than the normal compression value of the cylinder and of less value than the pressure of the cylinder developed by 30 the firing of the charge, whereby check-valve activity will be provided during the period of preponderant cylinder pressure to temporarily stop compressed fluid delivery to the cylinder, the ending of the delivery of such compressed fluid to the cylinder on its compression stroke and the beginning of the succeeding delivery to the cylinder during its 35 working stroke being dependent upon the length of time of the check-valve activity.

11. In means for starting multi-cylinder internal combustion engines, wherein the carburetted fluid for running purposes is supplied to the cylinder during the suction stroke 40 of the engine through the activity of a carburettor delivering the fuel content of the charge to the intake manifold, and wherein compressed fluid is admitted to and is active within the working cylinder to develop piston 45 movement in such cylinder during starting activity, a source of compressed fluid supply, and connections between such supply source and individual cylinders of the engine, said connections including valve mechanism for 50 controlling the delivery and distribution of 55 the fluid to the respective cylinders, and conduits leading from the valve mechanism to the cylinders individually with the mechanism having uniformly-spaced entrances to such conduits, each conduit having a check 60 valve adapted to be closed by cylinder pressure produced by firing of the charge, said mechanism including a rotatable member operatively connected to move in synchronism with the engine crank shaft, said member having a port adapted to be made active with the conduit entrances successively, said port 65 having dimensions and a configuration such that fluid will be delivered to the working cylinder to provide power therein and that fluid will also be delivered to the cylinder next in firing order to complete the air content of the charge of such latter cylinder prior to the firing period of the charge therein, the volume of fluid delivered to the working cylinder being materially greater than that delivered to the cylinder next in firing order.

In testimony whereof I affix my signature.

CHARLES F. HEYWOOD.
